ATTORNEY

UNITED STATES PATENT OFFICE.

WILLIAM LEE PILKINGTON, OF ST. HELENS, COUNTY OF LANCASTER, ENGLAND, ASSIGNOR TO PILKINGTON BROTHERS, OF SAME PLACE.

DESIGN FOR GLASS ORNAMENTATION.

SPECIFICATION forming part of Design No. 19,644, dated February 11, 1890.

Application filed December 7, 1889. Serial No. 332,967. Term of patent 14 years. Registered in England April 24, 1889.
No. 124,117.

To all whom it may concern:

Be it known that I, WILLIAM LEE PILKINGTON, of St. Helens, county of Lancaster, England, a subject of the Queen of Great Britain, have invented and produced a new and original Design for the Ornamentation of Glass, of which the following is a specification, reference being had to the accompanying drawings, forming part thereof.

10 Figure 1 is a plan view of a plate of glass showing my design, and Fig. 2 is an edge view of the same, these two views being deemed necessary to fully illustrate my design.

15 The leading feature of my design consists in a series of similar lozenge-shaped figures, which are each crowning or convex from their four sides or edges to the center of their faces in a continuous and uniform curve, and which are in juxtaposition at their like sides or edges, 20 and are separated or divided from each other at such adjoining sides or edges by two series of respectively parallel and intersecting depressions.

25 A A A are similar lozenge-shaped figures arranged in series and in juxtaposition at their like sides or edges. Each lozenge is crowning or convex from its four sides or edges to the center of its respective faces in

a continuous and uniform curve, as shown at *a*.

30

B B and C C are rectilinear depressions, which are respectively parallel in two series, as shown, and the respective series of parallels separate and divide the lozenge-shaped figures at their adjoining sides or edges and intersect at the angles thereof, as shown.

35 What I claim is—

The design for an ornamentation of glass herein shown and described, the same consisting in a series of similar lozenge-shaped figures A A A, which are each crowning or convex from their four sides or edges to the center of their faces in a continuous and uniform curve *a*, and which are in juxtaposition at their like sides or edges, and the two series 40 of respectively parallel rectilinear depressions B B and C C, which separate and divide the lozenge-shaped figures from each other at their adjoining sides or edges and intersect at the angles thereof, as set forth.

45 WM. LEE PILKINGTON.
